TYPEWRITER DESK

Clarence W. Koch, St. Louis, Mo.

Application August 14, 1939, Serial No. 290,122

7 Claims. (Cl. 312—22)

My invention relates to a desk adapted to accommodate a typewriting machine and particularly to the kind of desk known as a pedestal desk. Specifically, the present invention consists in certain improvements in the construction and mode of operation in the form of desk shown and described in my Patent No. 2,173,302 of September 19, 1939.

One of the objects of my invention is to provide improved means for locking the carriage in its forward or operative position.

Another object of my invention is to provide improved engaging means between the door and table.

Still another object of my invention is to provide means for preventing the table from swinging out of its vertical position when it is being moved into and out of the pedestal.

My invention also relates to various novel features and details of construction set forth in the following specification and pointed out in the claims.

In the accompanying drawings which illustrate one form of typewriter desk made in accordance with my invention Figure 1 is a perspective view, the right-hand pedestal alone being shown; Figure 2 is a section taken on the line 2—2 of Figure 7; the table being shown in vertical position; Figure 3 is a section taken on the line 3—3 of Figure 8; Figure 4 is a section taken on the line 4—4 of Figure 8; Figure 5 is a top plan view, the desk top being removed; Figure 6 is an enlarged section taken on the line 6—6 of Figure 7; Figure 7 is a section taken on the line 7—7 of Figure 8; Figure 8 is a fragmentary top plan view showing the table in horizontal position; and Figure 9 is a section taken on the line 9—9 of Figure 8.

The desk as shown in Figure 1 is arranged to receive the typewriting machine in the right-hand pedestal. It will be understood that this pedestal is connected to a second pedestal containing drawers or other receptacles for material. The pedestal comprises outer and inner side walls 10 and 11, respectively, a rear wall 12 and a top 13. The front of the pedestal is closed by a door 14 pivotally mounted by hinges 15 to the outer front corner post 16. The hinges are so constructed that when the door is in its open position, as shown in Figure 8, its inner face will lie substantially flush with the inner face of post 16. Secured to the outer front post 16 and the outer rear post 17 is a rail or plate 18 forming one of the supports for the carriage. The

other support for the carriage is provided by a rail 19 extending between the inner front corner post 16' and the inner rear corner post 17'. This rail is not secured to the posts but is carried on a reenforcing member 11' of the wall 11, being spaced therefrom by studs 20. The front end of this rail is provided with a turned over end 21 cooperating with carriage locking mechanism 22 which is like that shown in my patent above referred to and need not be described in detail.

The carriage comprises an approximately rectangular frame 23 provided at its end adjacent rail 18 with a downwardly extending end plate 24. Carried by this plate is a flanged roller 25 engaging with the upper edge of rail 18 and a second flanged roller 26 engaging with the lower edge of said rail. One side of the carriage is provided with an extension 27 projecting over the rail 18 and the plate 24 is provided with a pin 28 extending under said rail. The object of these parts 27 and 28 is to prevent tipping of the carriage on the rollers 25 and 26. The opposite end of the carriage is provided with a flanged roller 29 engaging with the upper edge of the rail 19, the lower edge being engaged by a pin 30 extending under said rail.

Secured to plate 24 is a U-shaped member 31 which forms the support for the inner ends of two aligning pivot pins or trunnions 32 from which the table 33 is supported. Surrounding these pins are straps 34 either formed integral with or secured to a plate 35 bolted to the rear end 33' of the table 33, which end is reduced in width relative to the main part of the table. Extending longitudinally of the carriage above the trunnions 32 is a threaded rod 36. Sliding on this rod is a collar 37, the position of which on the rod may be adjusted by a pair of nuts 38 and 39. To the collar is attached one end of a counter-balance spring 40, the other end of which is attached to the plate 35.

To provide means for preventing movement of the table into the pedestal when moved out of its vertical position, which means does not depend upon manipulation of locking devices but is positively controlled by the position of the table itself, I provide the lock shown in detail in Figures 2 and 3. A sliding bolt 41 is mounted on the carriage 23 and adapted to engage with a slot 42 in the rail 18. This bolt is connected to a lever 43 by a pin 41' passing through a slot 43' in the lever. The lever 43 is pivoted at 44 to the carriage and having a finger 45 adapted to be engaged by a corner of the plate 35, a portion 46 of the table end 33' being cut away for this pur-

pose. A spring 47 attached at one end to the lever 43 and at the other to the frame 23 serves to throw the bolt when not retracted by contact of plate 35 with finger 45.

When table 33 is in its vertical position, it rests against a filler block 48 secured to the wall 10. To retain the table in this position as it is moved into or out of the pedestal, it is provided with a hook 49 (Figure 3) which, when the table is lowered into vertical position, passes through an opening 50 (Figure 7) in the plate 24 and passes through a slot 51 in the rail 18 so as to engage with the outer face thereof as the table moves into or out of the pedestal. The table also has secured to its under face a track 52 which engages with a flanged wheel 53 and a pin 54 carried by a bracket 55 secured to post 16. This construction not only provides additional support for the carriage but prevents wobbling of the carriage and its attached table as they are moved into and out of the pedestal.

In my prior application above referred to, I have shown means, brought into operation by the movement of the table into horizontal position, for supporting the outer end of the table from the door and also for camming a stop on the carriage against a stop on its supporting rail to impart rigidity to the structure when the table is in operative position. In the present construction I have provided a device, shown in detail in Figure 6, which performs the same functions and in addition provides locking means for preventing lateral movement between the edge of the table and the door. The door is provided with a recess 56 adjacent which is secured a wear plate 57 having an inclined face 58 to produce the camming effect. In the present structure the projecting end of one side of the frame 23 may form the carriage stop adapted to be drawn against a stop 59 on the rail 18. The recess 56 extends below the edge of the body of the wear plate so that its rear face may be engaged by an overturned lip 60 on a plate 61 secured to the edge of the table. This provides a positive locking engagement to prevent lateral movement between the parts.

The typewriting machine 62, shown in dotted lines in Figure 5, may be secured to the table by means of bolts or screws passing through holes 63 in the table into the frame of the machine. A handle 64 is provided for use in raising and lowering the table. The table is provided with a buffer 65 of leather, rubber or the like to contact with the lower edge of the carriage.

In the operation of my desk, the parts being in the position shown in Figure 5, the door is first opened to the position shown in Figure 7. The table is then drawn outwardly by grasping the handle 64. During this movement, the engagement of the hook 49 with the rear face of rail 18 and the engagement of the table with the filler block 48 prevent any movement of the table from vertical position in either direction. Also, the engagement of rail 52 with roller 53 and pin 54 prevents wobbling of the table and carriage which otherwise might occur. The table is now swung into its horizontal position to engage it with the locking mechanism 22. During the first part of this movement the corner of the plate 35 recedes from finger 45, permitting spring 47 to move bolt 41 into engagement with slot 42 to lock the carriage against inward movement during the upward movement

of the table and before the locking mechanism 22 is brought into operation. The table is held in horizontal position by the engagement of lock 22 with the turned over end 21 of rail 19.

5 When in this position, the engagement of lip 60 with plate 57 effectively prevents lateral movement between the door and table. The arrangement of rod 36, providing adjustment for the counter-balance spring 40, above the trunnions 32 permits the adjustment to be so made that when the table is in vertical position, the spring connection will be swung past the trunnions 32 as shown in dotted lines in Figure 9. When in this position, the tension of the spring does not tend to raise the table but to throw it against filler block 48. This adjustment is of importance when the desk is being shipped or at other times when no machine is attached to the table as it obviates the possibility of violent upward jerk 10 of the table when it is drawn forward. When a machine is on the table, the adjustment is made to throw the spring connection past the trunnions in the other direction (toward the right-hand side in Figure 9). The amount of this 15 adjustment will depend upon the weight of the machine as movement of the spring connection past the axis of the trunnion (in the direction stated) will increase the distance between the attachment of the spring to collar 37 and its attachment to plate 35 when the table is in vertical position, and hence its tension at time of starting to raise the table. The division of the trunnion into two parts, between which the spring connection may swing, facilitates the 20 securing of the desired results as it permits the moving of the spring connection past the trunnion axis without tendency to skew the parts such as would result from arranging the connection at one end of the trunnion.

25 40 Having fully described my invention, what I claim as new and desire to secure by Letters Patent of the United States is:

1. In a device of the class described, a desk 45 provided with a pedestal, a carriage slideable in said pedestal, a table pivotally mounted on said carriage to swing from a horizontal to an approximately vertical position on an axis parallel with the direction of travel of the carriage, a sliding bolt on the carriage engaging with a fixed portion of the desk, and a lever for controlling the movement of said bolt, means whereby said lever is operated by substantial movement of the table from its normal vertical position.

2. In a device of the class described, a desk 50 provided with a pedestal, a carriage slideable in said pedestal, a table pivotally mounted on said carriage to swing from a horizontal to an approximately vertical position on an axis parallel with the direction of travel of the carriage, a rail supporting one end of said carriage, an end plate for the carriage extending downwardly adjacent said rail and provided with means engaging the lower edge of the rail, an opening in said end plate, a notch in said rail, and a hook carried by the table passing through said opening and notch to engage the rear face of the rail as the carriage and table are moved into or out of the pedestal.

3. In a device of the class described, a desk 55 provided with a pedestal, a carriage slideable in said pedestal, a table pivotally mounted on said carriage to swing from a horizontal to an approximately vertical position on an axis parallel with the direction of travel of the carriage, a

door for said pedestal, said door being unconnected with the table when the latter is in perpendicular position, and means carried by the table forward of the carriage engaging with an abutment on the door to support the table when the latter is in horizontal position, said means interlocking with the abutment to prevent lateral movement between the door and table.

4. In a device of the class described, a desk provided with a pedestal, a track in said pedestal, a carriage mounted on said track to travel from front to rear of the pedestal, a trunnion carried by said carriage and positioned a substantial distance from one end thereof, a table pivoted to said trunnion, a counter-balance spring connection extending from a point above the trunnion axis to said table, and adjusting means for moving said connection from one side of the trunnion axis to the other.

5. In a device of the class described, a desk provided with a pedestal, a track in said pedestal, a carriage mounted on said track to travel from front to rear of the pedestal, a two-part trunnion carried by said carriage and positioned a substantial distance from one end thereof, a table pivoted to said trunnion, a counter-balance spring connection extending from a point above the trunnion axis to said table, and adjusting means for moving said connection from one side

of the trunnion axis to the other at a point between the parts of said trunnion.

6. In a device of the class described, a desk provided with a pedestal, a track in said pedestal, a carriage mounted on said track to travel from front to rear of the pedestal, a trunnion carried by said carriage and positioned a substantial distance from one end thereof, a table pivoted to said trunnion, a threaded rod carried by the carriage and positioned above the axis of the trunnion, a collar on said rod, a counter-balance spring connection extending from said collar to said table, and means for adjusting the collar on the rod to move the connection from one side of the trunnion axis to the other.

7. In a device of the class described, a desk provided with a pedestal, a track in said pedestal, a carriage mounted on said track to travel from front to rear of the pedestal, a two-part trunnion carried by said carriage and positioned a substantial distance from one end thereof, a table pivoted to said trunnion, a threaded rod carried by said carriage and positioned above the axis of the trunnion, a collar on said rod, a counter-balance spring connection extending from said collar to the table, and means for adjusting the collar on the rod to move the connection from one side of the trunnion axis to the other at a point between the parts of said trunnion.

CLARENCE W. KOCH.
